(57) **CLAIM**

I claim the ornamental design for a nipper, as shown and described.

DESCRIPTION

FIG. 1 is a perspective front upper view of a nipper showing my new design;

FIG. 2 is a perspective rear upper view thereof;
FIGS. 3 and 4 are front and rear elevation views thereof,

respectively;

FIGS. 5 and 6 are top plan and bottom plan views thereof,

respectively; and,

FIGS. 7 and 8 are left and right side views thereof, respec-

tively.

The broken lines shown represent unclaimed subject matter

and form no part of the claimed design.
